VICTOR GAERTNER

By his Attorney

Charles E. Gile

UNITED STATES PATENT OFFICE.

VICTOR GAERTNER, OF NEW YORK, N. Y., ASSIGNOR TO CONTINENTAL SHEFFIELD
SILVER CO., OF BROOKLYN, NEW YORK, A FIRM.

DESIGN FOR AN ARTICLE OF HOLLOW TABLEWARE.

55,161.

Specification for Design.

Patented May 18, 1920.

Application filed February 27, 1920. Serial No. 361,649. Term of patent 14 years.

To all whom it may concern:

Be it known that I, VICTOR GAERTNER, a citizen of the United States, residing at New York city, in the county and State of New York, have invented a new, original, and ornamental Design for an Article of Hollow Tableware, of which the following is a specification, reference being had to the accompanying drawings, forming a part thereof, and in which—

Fig. 2 a side elevation of an article of hollow tableware embodying my design.

I claim:

The ornamental design for an article of hollow tableware, as shown.

VICTOR GAERTNER.
